US00D944383S

(12) **United States Design Patent** (10) Patent No.: **US D944,383 S**
Jin et al. (45) Date of Patent: **** Feb. 22, 2022**

(54) **AROMA DIFFUSER**

(71) Applicant: **SHENZHEN QIANHAI PATUOXUN
NETWORK AND TECHNOLOGY
CO., LTD.**, Shenzhen (CN)

(72) Inventors: **Jingxiao Jin**, Shenzhen (CN);
Tingsheng Wang, Shenzhen (CN);
Chengwu Wang, Shenzhen (CN)

(73) Assignee: **SHENZHEN QIANHAI PATUOXUN
NETWORK AND TECHNOLOGY
CO., LTD.**, Shenzhen (CN)

(**) Term: **15 Years**

(21) Appl. No.: **29/780,222**

(22) Filed: **Apr. 23, 2021**

(51) LOC (13) Cl. **23-04**

(52) U.S. Cl.

USPC **D23/366**

(58) **Field of Classification Search**

USPC D23/209, 355, 356, 358, 359, 360, 364,

(57) **CLAIM**

The ornamental design for an aroma diffuser, as shown and described.

DESCRIPTION

FIG. 1 is a perspective view of an aroma diffuser showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the aroma diffuser that form no part of the claimed design.
